UNITED STATES PATENT OFFICE.

JOHN W. KENNEDY, OF WILLINGHAM, GEORGIA, ASSIGNOR OF ONE-HALF
TO M. A. SAXTON, OF SAME PLACE.

PISTON-PACKING.

SPECIFICATION forming part of Letters Patent No. 611,433, dated September 27, 1898.

Application filed September 9, 1897. Serial No. 651,118. (No model.)

To all whom it may concern:

Be it known that I, JOHN W. KENNEDY, a citizen of the United States, residing at Willingham, in the county of Worth and State of Georgia, have invented certain new and useful Improvements in Piston-Packings; and I do declare the following to be a full, clear, and exact description of the invention, such as will enable others skilled in the art to which it appertains to make and use the same.

My invention has relation to piston-packings; and the object is to provide a packing of this character which will stand wear and tear, lubricate the piston or other rod which works through it, and provide a steam and water tight joint.

With this object in view the invention consists, broadly, in a packing composed of strings of cotton, hemp, asbestos, or any other fibrous material, said strings being rubbered or gummed separately and saturated in a solution of graphite and lubricating-oil.

In making the packing I first take several strings of fibrous material—such as cotton, hemp, or asbestos—and provide them with a serving of rubber, which lies upon the string in the form of separated flakes in order to insure an increased flexibility of the string. I then saturate the strings in a solution of graphite and lubricating-oil. The advantages of a packing of this composition are, first, that it is more convenient for use in any size stuffing-box than round, square, or any other design of rubber packing and is more durable for the reason that the fiber all runs the

same way or practically parallel and when it becomes heated makes a solid ring of elastic packing. Another convenience and advantage is that one size will fit all sizes from the smallest valve to the largest piston-rod, as it will be sold in rolls or hanks, and any quantity of the strands can be separated from the rolls or hanks and used as desired. This is a great advantage over the rubber packings, as the main objection to them is, as all consumers know, the necessity of having to carry the different sizes in stock to fit every size of valve or stuffing-box.

A packing of the material above described is antifriction, as the graphite is equally distributed throughout the packing and is in constant contact with the piston-rod or valve-stem.

The packing retains its elasticity, as the rubber is equally distributed through the packing, and a slight pressure on the gland or packing-nut will at all times stop any leak, thereby giving always a perfect steam-joint.

What I claim is—

A packing for the purpose set forth consisting of strings provided with a serving of separated rubber flakes, and saturated in a solution of graphite and lubricating-oil, substantially as and for the purpose set forth.

In testimony whereof I hereunto affix my signature in presence of two witnesses.

JOHN W. KENNEDY.

Witnesses:

I. LIPTAN,
ISAAC HOWARD.
